SACHET COVER

Charles Grabley, Richmond Hill, N. Y.

Application February 15, 1950, Serial No. 7,942

Term of patent 14 years

(Cl. D86—10)

To all whom it may concern:

Be it known that I, Charles Grabley, a citizen of Germany, residing at Richmond Hill, county of Queens, State of New York, have invented a new, original, and ornamental Design for a Sachet Cover, of which the following is a specification, reference being had to the accompanying drawing, forming part thereof.

Fig. 1 is a perspective view of a sachet cover showing my new design;

Fig. 2 is a developed plan view of the sachet cover.

I claim:

The ornamental design for a sachet cover, substantially as shown.

CHARLES GRABLEY.
